DISPOSABLE DIAPER

George C. Hansen, Haverford, Pa.

Application November 19, 1956, Serial No. 622,869

2 Claims. (Cl. 128—284)

This invention relates to a disposable diaper.

In its preferred embodiment as herein disclosed, the diaper comprises an inner pad of partly refined pulp which has been stabilized by spraying with adhesive. The stabilization of a pulp pad in this manner is not herein claimed, comprising the subject matter of a separate application.

The partial refinement of the pulp has to do with the degree to which its fibers have been separated. In the original wood, the fibers are, of course, bonded together. In the pumping operation, the fibers are torn apart and the bonding agent present in the growing timber is eliminated. Nevertheless, considerable adhesion between individual fibers remains and in the refining operations these are mechanically separated by known procedures. The present invention requires that the refining operation be stopped at an intermediate point. If the refining is insufficient, the pulp will be coarse and harsh to the touch. If the refining is carried to a maximum degree, the fibers will not only be separated but broken up to such a point that the resulting pulp pad will have the action of a wick and tend to disseminate rather than to retain the liquids it is designed to catch and hold.

The refined pulp is formed into a batt by procedures forming no part of the present invention and this batt is first sprayed with a sizing adhesive and is then laminated to backing and facing plies, both of which are porous or absorbent, the preferred difference lying in the fact that the facing ply is desirably a non-woven fabric and the backing ply a porous wet strength paper. One or more plies of absorbent paper may be placed between the basic facing ply and the pulp pad to effect dispersion of liquids and to render the pad softer by preventing pulp fibers from protruding through the facing ply. A wide variety of adhesives may be used for sizing, including dextrin, starch, resin or latex in any liquid vehicle suspension. The amount of dilute adhesive used may vary from one to five grams per diaper of seven inches by sixteen inches and the degree of concentration is indicated by the fact that this will ordinarily represent a range of seven-tenths of a gram to 1.5 grams of adhesive solids per diaper. Products of other dimensions would, of course, be treated proportionately.

In the assembly of the product, the facing web and the web or webs of underlying tissue, if any, are fed beneath the advancing web of pulp, one or both surfaces of which have been freshly sprayed with sizing. The rear face of the web of pulp is always sized. When the front face of the pulp web is sized, underlying tissues will always be employed. The facing web is made materially wider than the web of sized pulp and the margins of the facing web are turned over onto the exposed face of the pulp and subjected to the action of gluing rolls after which the backing web is applied and subjected to pressure to bond it securely to the inturned margins of the facing web.

Finally, the resulting laminated web is cut into individual diaper lengths and the end margins of the indi-

2

vidual diapers are subjected to heavy sealing pressure. Undoubtedly, the seal is partially attributable to the still adhesive surfaces of the fiber of the pad, but it is believed that the embossing pressure exerted thereon is primarily responsible for closing the ends of the diaper and interlocking the fibers of the pad with each other and with the backing and facing sheets. It is considered very desirable that the pulp extend to the end of the pad to intervene between the facing and backing sheets at all points, clear to the ends of the diaper.

In use, the diaper is desirably held to the child's body by some means other than itself. It can, for example, be supported by a conventional cloth diaper. Desirably, the diaper of the present invention is used as an insert in a specially designed, moisture-proof garment which is here illustrated but is not claimed herein, since it forms the subject matter of another application.

In the drawings:

Fig. 1 is a view in perspective of a complete diaper embodying the present invention, portions thereof being broken away to expose interior plies.

Fig. 2 is a view in cross section through the diaper shown in Fig. 1.

Fig. 3 is an enlarged fragmentary detail view of an end portion of the diaper in inverted plan.

Fig. 4 is a detail view on a further enlarged scale taken on line 4—4 of Fig. 3.

Fig. 5 is a view in perspective showing the diaper of the present invention introduced into the garment for purposes of application to a child.

Fig. 6 is a diagrammatic view in longitudinal section showing, merely by way of exemplification, a series of procedural steps in the production of the diaper of the present invention.

As already indicated, the preferred practice involves use of a non-woven fabric for the facing ply 1 which represents the top surface of my improved diaper. Beneath this there is optionally incorporated one or more plies 2 of absorbent paper tissue of the grade of facial tissue or the like.

The center of the diaper comprises a pad 3 of partly refined pulp stabilized or bonded by minute quantities of adhesive which connect its fibers at innumerable points, the adhesive being used so sparingly that it does not stiffen the pulp pad.

The bottom of the pad comprises a backing ply 4 of paper of high wet strength but nevertheless porous. The diaper is made relatively thin. For some babies, a single diaper of this weight is ample. However, it is an important feature of the present diaper that the backing sheet as well as the facing sheet be porous and permeable so that, when a plurality of diapers are used simultaneously, liquid will pass from one to another to neutralize the absorbent capacity of them all.

The width of the facing ply 1 preferably exceeds the width of the pulp pad 3 sufficiently to permit the side margins 5 of the facing ply to be turned over the edges of the pad and to receive bonded connection with the backing ply 4 which is held thereto by an intervening strip of adhesive shown at 6 in Fig. 2.

The pulp pad 3 projects to the end of the diaper as shown at 7 in Fig. 4. At its ends, the diaper is of considerably reduced thickness by reason of embossing 8 (Fig. 3) which actually unites the fibers, as is well known in the paper converting field. The adhesive size with which the fibers of the pad 3 have been sprayed will bond the backing ply 4 to pad 3 and will also assist in closing the ends. When sizing is sprayed on the front of the batt, it will bond the pad 3 to the tissue. The intermittent and/or adhesive connection of the several plies as a result of the embossing operation at the ends of the diaper desirably stiffens these ends, this being advan-

tageous in holding the diaper securely in position in such a garment as that shown in Fig. 5.

In use, the end portions of the resulting diaper, generically designated by reference character 10 in Fig. 5, are inserted beneath the overhanging web portions 11 of a garment 12 which has elastic side flaps at 13 and 14 and glove fasteners or other connecting means whereby the side flaps may be connected to each other and to the upwardly folded end portions 15. Further details of this garment are not required, since it forms no part of the present invention. It is desired to note only that it is desirably made of waterproof but flexible material and has a large opening 16 through which most of the upper surface of the diaper 10 is exposed to receive bodily excretions from the child wearing the garment. The diaper is sufficiently flexible so that it is readily manipulated into place through this opening and is withdrawable with equal facility for disposal. The stiffness of the embossed diaper ends helps to hold the diaper flat and in place. The entire diaper is desirably made of pad and tissue materials capable of disintegration in water to facilitate disposal.

With reference to Fig. 6, it will be understood that the diagrammatic disclosure in this view is solely by way of exemplification. It does not represent the only way in which the diaper can be manufactured.

From the parent roll 18 of pulp, the pulp web 19 passes between upper and lower spray nozzles 20 and 21, nozzle 20 spraying adhesive sizing upon the upper surface of web 19 (as viewed in Figure 6) and, if desired, nozzle 21 spraying adhesive sizing on the lower surface.

Beneath the path of the pulp web are supply rolls 22 and 23 from which the webs 24 of top facing material and 25 of tissue material pass into lamination with the then lower surface of the pulp web. The margins of

web 24 are turned by conventional formers at 26 to lie about the edges of the pulp in the manner already disclosed and these margins are then treated with adhesive by the glue roll 27 so that the bottom or backing ply 30 fed from supply roll 31 will adhere thereto under pressure of sealing rolls 32 and 33.

As shown at 34 and 35, conventional cutting and embossing dies sever the individual diapers and seal their ends in the manner above described.

I claim:

1. A multi-ply diaper for use as an insert in a garment diaper holder comprising a batt of partially refined pulp, the back of said batt being sized, a porous non-woven fabric facing ply overlying the front face of the batt and having margins overturned onto the back of the batt, a porous wet strength paper backing ply secured to the batt by the said sizing and adhesively secured to the margins of the facing ply, said batt extending to both ends of the diaper and the ends of the diaper being closed and stiffened by being compressed.

2. A multi-ply diaper for use as an insert in a garment diaper holder comprising a batt of partially refined pulp, the back of said batt being sized, a porous non-woven fabric facing ply overlying the front face of the batt and having margins overturned onto the back of the batt, a porous wet strength paper backing ply secured to the batt by the said sizing and adhesively secured to the margins of the facing ply, said batt extending to both ends of the diaper and the ends of the diaper being closed and stiffened by embossing.
